UNITED STATES PATENT OFFICE.

CHARLES D. McCORD AND JOHN L. CARLSON, OF EDENBURG, PENNSYLVANIA.

SHADE-HANGER.

1,253,699.

Specification of Letters Patent. Patented Jan. 15, 1918.

Application filed July 29, 1916. Serial No. 112,078.

To all whom it may concern:

Be it known that we, CHARLES D. McCORD and JOHN L. CARLSON, citizens of the United States, residing at Edensburg, in the county of Lawrence and State of Pennsylvania, have invented certain new and useful Improvements in Shade-Hangers, of which the following is a specification.

This invention relates to an improved shade roller and curtain pole holder and the principal object of the invention is to provide a holder which will protect the roller from dust and thus prevent it from becoming soiled.

Another object of the invention is to so construct the holder that it may be adjusted according to the length of the shade roller.

Another object of the invention is to so construct the holder that it may be very easily put in place.

Another object of the invention is to so construct this shade holder that the curtain pole supporting arms or brackets may be releasably connected therewith.

Another object of the invention is to so construct the holder, that in one form it may be connected with the outer faces of the side portions of a window frame and in a modified form, it may be connected with the inner faces of the side portions of a window frame.

This invention is illustrated in the accompanying drawings, wherein:—

Figure 1 is a view in front elevation of one form of the shade holder.

Fig. 2 is an end elevation of the shade holder shown in Fig. 1.

Fig. 3 is a top plan view of the intermediate portion of the shade holder shown in Fig. 1.

Fig. 4 is a sectional view taken along the line 4—4 of Fig. 1.

Fig. 5 is a fragmentary sectional view through one end of one of the sections of the shade holder shown in Fig. 1.

Fig. 6 is a view in elevation of one end portion of the modified form of holder from that shown in Fig. 1.

Fig. 7 is a view in end elevation of the form of holder shown in Fig. 6.

Fig. 8 is a view similar to Fig. 4 of the form of holder shown in Figs. 6 and 7.

Fig. 9 is a view in rear elevation of a modified form of holder from that shown in the previous figures.

Fig. 10 is a top plan view of the form of holder shown in Fig. 9.

Fig. 11 is a view similar to Fig. 9 of a slightly modified form of holder.

Fig. 12 is a view partially in top plan and partially in longitudinal section of the form of holder shown in Fig. 11.

Fig. 13 is a top plan view of the holder shown in Figs. 11 and 12.

In the form shown in Figs. 1 through 5 and in Figs. 9 and 10, the curtain holder is to extend against the outer faces of the side portions of the window casing and in the form shown in Figs. 6 through 8 and 11 through 13, the shade holder is to fit between the side portions of the window frame. In the form shown in Figs. 1 through 5, the shade holder is formed of sheet metal and is provided with end sections indicated in general by the numeral 10. As each of these end sections has the same construction, a description of one will suffice for both. The blank from which the end section is formed is bent longitudinally to provide a rear wall 11 and an upper wall 12, the outer one of which is provided with a longitudinally extending slot 13 through which passes a securing bolt 14 carried by the upper wall of the inner section. Therefore this shade holder may be longitudinally adjusted and releasably held in the adjusted position. The outer end portion of the upper wall is separated from the rear wall and is bent downwardly thus providing an end wall 15 and an ear 16, the ear being provided with an opening to receive the securing screw 17. It should be noted that this securing screw 17 is provided with an enlarged head so that it may be turned easily and thus screwed into place. Tongues 18 are struck from the rear wall and are bent and passed through slots formed in the end wall thus securely holding the end walls in the desired position. Clamping tongues 19 are struck from this end wall 15 above and to one side of openings 20 and it will thus be seen that the arms 21 of the curtain pole supporting brackets 22 may be passed under the clamping tongues 19 and have their hooked ends 23 passed through the openings 20 thus releasably but securely connecting the curtain pole supporting brackets with the end wall.

It should be further noted that the upper wall has its outer edge portion bent downwardly to provide a depending flange 24 and that the end walls are stamped to provide sockets 25 one of which will be provided with a circular opening and the second with a slot. When in use this curtain pole and

shade roller hanger will be adjusted to the length of the shade roller and the securing bolt 14 then tightened and the holder can then be put in place and secured by means 5 of the fasteners 17.

In the form shown in Figs. 6, 7 and 8, there has been provided a shade roller holder which is somewhat similar to the form shown in the previous figures and in which each 10 end section is provided with an upper wall 26, a rear wall 27 and a front 28 and an end wall 29. The front and rear walls are provided with end flanges 30 which are bent inwardly and fit against the end wall, 15 tongues 31 being struck from the end wall and bent to extend through slots in the flanges 30 to securely connect the flanges with the end wall. These end walls extend beneath the front and rear walls and are 20 provided with fastener receiving sockets 32 through which the fasteners 33 may be passed to connect the end walls with the inner faces of the side portions of a window casing. This form of roller holder will be 25 used in a manner similar to that previously described and will be adjusted to the proper length with the pivot pin and winding key of the roller fitting into the sockets 34 and the securing bolts 35 will then be tightened. 30 The secured screws 33 will then be put in place and the holder will be connected with the window frame. It will thus be seen that with the forms described, the rollers will not only be protected from dust but will be 35 further prevented from working loose as the holder in both cases is adjusted to the proper length and therefore the roller cannot slip out of place.

In the form shown in Figs. 9 through 13, 40 the housing may be formed in two sections 36 which may be constructed substantially the same as shown in the previous figures, the two sections being adjustably connected and releasably held in an adjusted position 45 by the screws or bolts 37. The rear wall of the housing in the form shown in Figs. 9 and 10 will be provided with slots or openings 38 to receive the teeth 39 of the supporting bracket 40. This supporting bracket 50 40 is provided with hinge ears 41, a cam roller 42 is rotatably mounted between the hinge ears 41 and is positioned between the abutment fingers or shoulders 43 and 44 of the clamp 45. This clamp 45 is slidably 55 mounted and has its penetrating arms or teeth 46 engaged by the tongues 47 carried by the flange 48 of the bracket 40 and it will be readily seen from an inspection of Figs. 9 and 10 that by turning the cam 60 roller through the medium of the actuating handle or lever 49, the clamp can be moved into or out of an operative position.

In the form shown in Figs. 11 and 12, the

clamp is of the same structure as that shown in Figs. 9 and 10 and therefore the same reference numerals have been used. In this case, however, the hinge ears 49 are formed from tongues struck from the rear walls of the housing and the brackets 40 of Figs. 9 and 10 will thus be done away with and 65 the clamp will fit directly against the rear wall of the housing and have its arms slidably held in place by tongues 50 similar to the tongues 47 but struck from the rear wall of the housing. The cam roller 51 will be 70 rotatably mounted between the hinge ears 49 and by turning the cam roller through the medium of the handle 52, this clamp can be moved into and out of an operative position. It is of course, obvious that if desired, 75 the housing shown in Figs. 1 through 8 could be provided with the clamp shown in Figs. 9 through 13.

What is claimed is:—

1. A shade roller support comprising a 85 housing, including adjustably connected end portions, each provided with a rear wall, an upper wall, and end walls, the end walls being provided with openings in their lower end portion and having tongues struck from 90 their upper end portions and bent to provide clamps, and curtain pole supports including arms engaged by the clamping tongues and having their end portions bent to provide fingers extending through the openings of 95 said end walls.

2. A shade roller and curtain pole support comprising a housing including end walls provided with shade roller receiving sockets, the end walls being provided with 100 openings adjacent their lower ends and having tongues struck from their upper end portions and bent to provide clamps, and curtain pole supporting brackets including arms extending along the end walls and engaged by said clamping tongues and having their end portions provided with fingers extending through the openings of the end walls.

3. A curtain pole support comprising a 110 housing including end walls having openings formed therein and having tongues struck therefrom and bent to provide clasps positioned above the openings, and curtain pole supporting brackets including arms extending along the end walls and engaged by said clamping tongues and having their end portions provided with fingers extending through the openings of the end walls.

In testimony whereof we affix our signatures in presence of two witnesses.

CHARLES D. McCORD.

JOHN L. CARLSON.
